UNITED STATES PATENT OFFICE.

LEE DE CAMP, OF OKLAHOMA, OKLAHOMA.

ROAD MACHINE.

1,402,148.

Specification of Letters Patent. Patented Jan. 3, 1922.

Application filed January 19, 1920. Serial No. 352,397.

To all whom it may concern:

Be it known that I, LEE DE CAMP, a citizen of the United States of America, residing at Oklahoma city, in the county of Oklahoma and State of Oklahoma, have invented certain new and useful Improvements in Road Machines; and I do hereby declare the following to be a full, clear, and exact description of the invention, such as will enable others skilled in the art to which it appertains to make and use the same.

This invention relates to a road surfacing machine, and for its primary object and purpose it is designed to readily, efficiently and economically smooth and resurface roads of various types, acting to grind off projections and humps in the road and deliver road material gathered by such operation either to small depressions and hollows in the road or to one side of the road. A further object of the invention is to so construct the machine, particularly the rotating operating drum thereof, that the projecting ribs extending radially from the drum may be readily replaced when worn out by others, and at the same time by merely reversing the position of the drum with respect to the remainder of the machine, whenever such ribs become dulled on one side, it is possible to operate the machine until the ribs are entirely worn out without removing the same for grinding or otherwise refitting them, said ribs when reversed in position being in shape from the wear imparted by operation of the machine to the opposite sides to continue operation without further refitting.

Various other objects and purposes other than those specifically stated above will appear as understanding is had of the invention from the following description taken in connection with the accompanying drawings illustrating the invention, in which drawings,

Fig. 1 is a plan view of the road surfacing machine.

Fig. 2 is a side elevation thereof.

Fig. 3 is a side elevation of one of the sections used in making up one of the projecting ribs on the rotating drum, and

Fig. 4 is an end view thereof.

Like reference characters refer to like parts in the several views of the drawing.

In construction, a strong and rigid frame is made comprising substantially two con-

nected but spaced apart trusses, each having a lower member 1, vertical posts 2, top member 3 and diagonal end members 4 as shown in Fig. 1. The lower members of the trusses are connected by cross ties 5 and the upper members by ties 6. The members of the truss and the ties are formed from well known commercial forms of iron such as channels and angle irons and a very strong and rigid frame may be made therefrom. At the front end additional members 7 and 7^a, members 7 being angularly positioned, are used being connected to the lower members 1.

A main shaft 8 is disposed transversely of and below the frame having suitable bearings at its ends connected to the frame members 1. On said shaft two large wheels 9 are secured the same serving to carry the entire machine and rotating shaft 8 when the machine is moved. The main shaft is located ahead of the centre of gravity of the machine whereby there is a tendency for the rear portion of the frame to drop. A post 10 pivotally depends from the under rear part of the frame and is of service to hold the same in upper position, swinging to the rear however when the machine is moved and freely passing over obstructions as indicated in dotted lines in Fig. 2. The members 7 and 7^a of the frame serve as a forward projecting portion which at its centre may be shaped to have attachment to any suitable motor or other power, preferably, a tractor for moving the machine along the road.

Main shaft 8 at each end is equipped with a gear 12, each meshing with a gear 13 mounted on a stud shaft 14 back of the main shaft. Alongside each gear 13 a sprocket wheel 15 is also mounted rotating with its associated gear 13. A bar 16 is loosely mounted at its upper end on each of the shafts 14 extending downwardly and to the rear and being formed with a bearing at its lower end to receive a stud 17 projecting from a head 18 fixed in the end of a hollow cast metal drum 19, whereby said drum is rotatably carried between the bars 16. A sprocket wheel 20 is secured at each end of the drum and a sprocket chain 21 is passed around wheel 15 and 20 at each side of the machine, it being evident that the drum is driven when the machine is moved over the

road; and the speed of driving may be regulated by the sizes of the sprocket wheels which may be changed so as to give different speeds desirable for different characters of roads.

A cable 22 is used at each end of the drum for raising and lowering the same, said cable passing through pulley blocks 23 one of which is suspended from a hook 24^a attached 10 to a bracket which in turn is fixed to an upper portion of the frame, while the other is attached to a hook 25 secured adjacent the lower end of bar 16. The construction on each side of the machine is the same in this 15 connection and through it the drum is raised or lowered as desired.

In the length of the drum and on its outer surface dove-tailed grooves are formed spirally in which sections 26 having bases 20 27 to fit the grooves are located, a plurality of sections in alinement making a spirally positioned rib on the drum. A plurality of said ribs are thus made in spaced apart relation around the entire surface of the drum 25 and when the drum is driven in lower position, and adjacent the surface of the road, the ribs serve to cut and grind off any humps or projections leveling the same while the spiral character of the ribs causes the material removed by the ribs to work to one 30 side, filling up any depressions and delivering any excess at the side of the road. Moreover, the wear on the ribs follows lines substantially parallel to the dotted line 28, Fig. 35 4, and after the ribs on one side have become considerably worn, it is only necessary to reverse the drum, changing it end for end whereupon the opposite sides of the ribs are sharp and in good condition for service. 40 Accordingly, it is never necessary to remove the ribs for sharpening, but when a rib or ribs have become entirely worn out, the same may be readily removed and new ribs used in replacement.

45 From the foregoing it will be apparent that I have made a strong and durable road surfacing machine which may be used on many types of roads. Dirt, gravel, macadam and even brick pavements may be 50 ground to smooth condition by use of this machine and a large amount of road repair may be accomplished at a minimum cost. Various details of construction may be changed without departing from the invention, and I do not wish to be limited to the 55 specific disclosure made but consider myself entitled to all modifications in construc-

tion falling within the scope of the appended claims defining the invention.

I claim:

1. A drum for road surfacing machines comprising a cylinder of cast metal formed with a plurality of grooves positioned lengthwise and spirally in the outer portions of the drum and extending from one end of the same to the other, a rib removably located in each groove and projecting outwardly from the drum, each of said ribs being formed of a plurality of contiguous short sections located in alinement, substantially as described.

2. A drum for road surfacing machines comprising a hollow cylinder of cast metal formed with a plurality of dove-tailed grooves positioned spirally and lengthwise of the drum from one end of the same to the other, said grooves being spaced from each other around the drum, and a rib removably located in each groove and extending the entire length of the same and projecting outwardly from the drum, each rib being formed with a base to slidably enter a groove at an end thereof to fit the dove-tailed form of the groove and be thereby held on the drum.

3. A drum for road surfacing machines comprising a hollow cylinder of cast metal formed with a plurality of dove-tailed grooves positioned spirally and lengthwise of the drum from one end of the same to the other, said grooves being spaced from each other around the drum, a rib removably located in each groove and projecting outwardly from the drum, each rib being formed of a series of short contiguous sections located in alinement in a groove, each section having a base to slidably enter a groove at the end thereof, and a head closing each end of the drum, substantially as described.

4. A road surfacing machine including a frame, supporting wheels located under and substantially at the middle of the frame, a rotatably mounted drum back of the wheels and transversely of the frame, means to raise and lower the drum with reference to the frame, means to drive the drum from the wheels, and means on the drum for grinding projections and smoothing and leveling a road over which the drum is moved, the last mentioned means being adapted to move the material laterally of the machine, substantially as described.

In testimony whereof I affix my signature.

LEE DE CAMP.
